UNITED STATES PATENT OFFICE.

JAMES W. IVORY, OF PHILADELPHIA, PENNSYLVANIA.

DESIGN FOR A DENTAL TOOL FOR CARRYING AMALGAM.

SPECIFICATION forming part of Design No. 26,678, dated February 23, 1897.

Application filed June 12, 1896. Serial No. 595,361. Term of patent 14 years.

To all whom it may concern:

Be it known that I, JAMES W. IVORY, a citizen of the United States, residing in the city and county of Philadelphia, State of Pennsylvania, have invented and produced a new and original Design for a Dental Tool for Carrying Amalgam, of which the following is a specification, reference being had to the accompanying drawings, forming part thereof.

10 The leading feature of my design for a dental tool for carrying amalgam is a cup-shaped carrier on the end of shank thereof with indented ornamentations on the concave surface of said cup.

15 Figure 1 represents a side elevation of an

amalgam-carrier embodying my device. Fig. 2 represents a side elevation of the same at a right angle to Fig. 1.

In the drawings, A designates the shank of the tool, and B designates cups at the ends thereof. In the inner or concave faces of the cups are indentations C.

What I claim is—

The design for a dental tool for carrying amalgam, substantially as described and shown.

JAMES W. IVORY.
